WRIST EXERCISER

Lewis Sharp and Albert Sharp,
Huntington Park, Calif.

Application September 19, 1950, Serial No. 185,544

11 Claims. (Cl. 272—68)

1

The present invention relates to a device for exercising the wrist and arm muscles and has for its object to provide an exercising device of the type referred to which may be used without placing a load on the shoulder muscles. In such devices of the type herein considered which have come to our notice, a rod has been provided on which a drum has been mounted and a weight is held suspended from this drum. While a device of this type may be beneficial to the development of the wrist muscles it is also found that the load imposed upon the arm and shoulder muscles will largely counteract the benefits to the wrist muscles or at least compel the user to lay aside the device for extended rest periods during the exercising operation.

It is in view of the foregoing the particular object of the invention is to provide a wrist exercising device to which no weight is attached and which is so light that it can be handled by any person without any strain on the arm and shoulder muscles. It is a further object to provide a device which may be held in any desired position by the hands of the operator thereby further adding to the benefits of the use thereof. It may for instance be desired at the beginning to hold the exerciser in the hands with the elbow against the sides of the body then gradually to extend the arms horizontally and little by little to swing the arms vertically above the head while all the time moving the hands on the device for the proper operation thereof.

These and other objects of the invention will appear from the following detailed description particularly when reference is had to the accompanying drawing in which a preferred form of the invention is illustrated.

In the drawing:

Fig. 1 is a general view of a device embodying the invention and with parts thereof broken away for the sake of clearness;

Fig. 2 is a substantially corresponding cross-sectional view through the longitudinal center of the device and taken at right angles to Fig. 1;

Fig. 3 is a sectional view taken substantially on line 3—3 of Fig. 1 in direction of the arrow;

Fig. 4 is a similar view taken on line 4—4 of Fig. 1 in the direction of the arrow;

Figs. 5, 6 and 7 show details of the construction the importance of which is hereinafter fully explained;

Fig. 8 is an end view of the device taken in the direction of arrow 8 in Fig. 1; and

Figs. 9 and 10 illustrate other parts of the device the importance of which will hereinafter appear.

2

The device of the invention as illustrated in the drawing consists essentially of tubular members 1, 2, which may be and preferably are of the same length and diameter. These members 5 serve to support tubular hand grips 3, 4 which also may be identically shaped and the outer ends of which are inwardly extended to provide end walls 5, 6 coming to rest against the ends of the tubular members 1, 2. Between the tubular members is placed a spacer 10 which as best shown in Fig. 6 is centrally perforated to provide a squared passage 11 for a rod 12 of a size and shape to fit snugly within this passage. On this rod is placed a plurality of discs 13, 15 see also Fig. 7, the central perforations 14 of which are similarly shaped fittingly to ride on the rod 12. Diametrically opposed lips 15, 16 project from the periphery of the discs for engagement with recesses 17, 18 at the inner end 20 of the member 2, as best shown in Fig. 4. A cap 20 is shaped to fit snugly over the end of the hand grip 4 and a threaded stud 21 extends through a central perforation of this cap for engagement with internal screw threads of the 25 rod 12. The stud is rigidly secured to an outer cap 22, which latter is rotatable on the inner cap 20 for the purpose of adjusting the device to modify operation thereof as will be fully described presently. In order to reduce friction 30 between the outer and inner caps, it is found advantageous to place a metal washer 19 between these parts.

The tubular member 1 is operatively connected with the member 2 in the following manner. The rod 12 is extended a distance into the member 1 to form a support for a series of washers 23 having rectangular passages 24 therethrough of a size to slide fittingly on the rod, see also Fig. 10. Between these washers are placed discs 25, the central passages 26 of which are circular and of a diameter to slide fittingly on the rod, see Fig. 5. These discs are, like the disc 13, provided with opposed diametrically projecting lips 27, 28 of a size to ride within axially directed recesses 29, 30 at the inner end 45 of the member 1.

All of the aforementioned washers and discs are maintained in operative position on the rod 12 in any suitable manner, as by means of cotter keys 33, 34 of the rod, and they are arranged in such axially spaced relation to each other between these keys that no pressure is normally exerted against these parts. From this it follows that the grips 3 and 4 may be manually, 50 freely rotated in opposite direction; but it is also found that, when the cap 22 is rotated to cause

the stem 21 to advance into the rod, the latter will be axially moved to cause the cotter key 33 to commence to draw the washers 23 and discs 25 toward the central spacer 10 thereby to create friction between these washers and discs tending to resist relative rotation of the members of the device. It is in this manner possible gradually to increase this frictional resistance as required for the required exercise of the wrist and arm muscles.

The washers 23 and the spacer 10 should be made from fiber or other material of sufficient resilience to respond to fine rotative adjustment of the cap 22. The discs 13 and 25 should, on the other hand, be made from relatively hard material such as steel or other suitable metal. It is advisable in order to protect the fiber washer 23 at the end of the rod, to place a small metal washer 36 in front thereof, against which the cotter key 33 comes to rest.

As above stated, very fine rotative adjustment of the cap 22 is sufficient materially to increase frictional resistance between the washers and discs within the device. It has been found advantageous in order to assist the user in properly adjusting the tension of the device to suit particular exercise requirements to place on the end surface of the outer cap 22 indicating means in the form of a dial which is graduated into a specified number of units, there being in the present case 36 units represented by the numerals 6 to 36 indicated in Fig. 8. Unit graduations 38 may be placed along the inner edge of the cap for registration with a pointer 39 on the outer surface of the cap 20, substantially as indicated in Fig. 1.

It was above stated that the cap 22 is rotatable to draw the washers and discs against the central spacer 10. It is, however, required to provide additional means for maintaining the washers and discs in position within the member 1. The latter is for this purpose shown made with a recess 40 circumferentially extending from the side edge of the recess 29 a short distance away from the end of the member. It is to be understood that there is a similar recess 41 on the other side of the member, as indicated in dotted outline in Fig. 1. In assembling the device, it is merely required first to mount all of the washers and discs in position on the rod 12 and to lock them in position thereon by means of the cotter keys 33, 34. The rod assembly may then be pushed into the member 1, causing the lips of the discs 25 to enter the recesses 29, 30 of the member until the lips of the disc 25^a nearest the spacer 10 reach a position of registration with the recesses 40, 41. It is then merely required to apply a pointed tool to one of these lips and to apply pressure thereto to rotate the disc until the lips enter into and become completely seated within the recesses 40, 41.

An additional disc 45 is placed adjacent to the spacer 10 and the lips of this disc are bent inwardly, substantially as indicated at 46 in Fig. 2, a distance sufficient to reach across the disc 25^a, behind the lips thereof. The disc 25^a is in this manner held locked in position within the circumferential recesses 40, 41 of the tubular member. The disc 45, which is best shown in Fig. 9, may in all other respects be identical with the disc 25.

Upon completion of the above described operation of assembling the washers and discs on the rod 12 and before these parts are inserted into the tubular member 1, it becomes necessary to mount the hand grip 3 in position thereon. It is required for this purpose first to place within

the hand grip a metal washer 48. A cap 49 is seated on the end of the hand grip 3 and it is suitably locked in position thereon. Illustrative of such means, we have shown a rivet extended through the cap, the end wall 5 of the hand grip and the washer 48. The hand grip may then be pressed into position on the member 1, to be maintained in position thereon by the resilience of the rubber composition. The assembling operations may then be completed as above outlined.

After the device has been completely assembled, it is required to adjust the parts thereof to provide a desired initial degree of friction between the two ends thereof; whereupon the cap 20 should be rotated on the grip 4 to bring the pointer 39 into registration with the zero (or 36) graduation on the outer cap 22. Since the cap 20 is tightly fitted on the end of the soft rubber grip, it may be difficult so to rotate the cap and it may be found advantageous to provide a perforation at or in place of the pointer 39 of a size to receive therein a spanner wrench, by means of which the operation of adjusting the cap may be greatly facilitated.

It is seen from the foregoing description that we have provided a very light and sensitive device which is convenient to operate and readily adjustable by the user. But while we have illustrated a preferred form of the invention, it is not intended thereby to limit the invention to the particular arrangements, proportions and shapes shown, but we reserve the right to embody modifications within the scope of the claims hereto appended.

We claim:

1. A portable wrist exerciser comprising two cylindrical tubular members placed end to end and of substantially uniform diameter throughout the length of the exerciser, means seatable within said members to maintain the members axially interconnected for relative rotation in opposite directions, said means including a stem within one member extending a distance into the other member, the latter having axially directed recesses in the inner end thereof, a series of discs on said stem held against rotation within the recess of said other member, a series of friction washers between said discs and held against rotation on said stem, and externally operable means connected with the stem for moving said discs and washers into frictional engagement with each other thereby increasingly to resist relative rotation of the two members.

2. A portable wrist exerciser comprising two cylindrical tubular members placed end to end and of substantially uniform diameter throughout the length of the exerciser, means seatable within said members to maintain the members axially interconnected for relative rotation in opposite directions, said means including a stem within one member extending a distance into the other member, the latter having axially directed recesses in the inner end thereof, and slots circumferentially extending from said recesses near the inner end of the member, a series of discs having lips seatable in said recesses to maintain the discs unturned within the member, the innermost disc reaching a position of registration with said slots when the discs are seated in the member for rotating movement of its lips into said slots to check axial movement of the discs within the member, a series of friction washers between said discs and held against rotation on said stem, and externally operable means for moving said

discs and washers against said innermost disc and in frictional engagement with each other thereby increasingly to resist relative rotation of the two members.

3. A portable wrist exerciser comprising two cylindrical tubular members placed end to end and of substantially uniform diameter throughout the length of the exerciser, means seatable within said members to maintain the members axially interconnected for relative rotation in opposite directions, said means including a stem within one member extending a distance into the other member, the latter having axially directed recesses in the inner end thereof, and slots circumferentially extending from said recesses near the inner end of the member, a series of discs having lips seatable in said recesses to maintain the discs unturned within the member, the innermost disc reaching a position of registration with said slots when the discs are seated in the member for rotating movement of its lips into said slots to check axial movement of the discs within the member, a series of friction washers between said discs and held against rotation on said stem, externally operable means for moving said discs and washers against said innermost disc and in frictional engagement with each other thereby increasingly to resist relative rotation of the two members, and means for locking the innermost disc against return rotation.

4. A portable wrist exerciser comprising two cylindrical tubular members placed end to end and of substantially uniform diameter throughout the length of the exerciser, means seatable within said members to maintain the members axially interconnected for relative rotation in opposite directions, said means including a stem within one member extending a distance into the other member, said stem being internally threaded, a series of discs on said stem held against rotation within said other member, a series of friction washers between said discs and held against rotation on said stem, a screw in the end of the first named member seated in the threads of the stem, and a cap on said screw, said cap being rotatable on the end of the member to move the stem axially to bring the discs and washers into frictional engagement with each other thereby increasingly to resist relative rotation of the two members.

5. A portable wrist exerciser of substantially uniform cylindrical shape throughout the length thereof, the exerciser comprising right and left members, means seatable within the exerciser to maintain the two members axially interconnected for relative rotation in opposite directions, said means including a stem within the right member extending a distance into the left member, a series of discs on said stem held against rotation within said left member, a series of friction washers between said discs, said washers being held against rotation on said stem, and externally operable means connected with the stem for moving said discs and washers into frictional engagement with each other thereby increasingly to resist relative rotation of the two members.

6. A portable wrist exerciser of substantially uniform cylindrical shape throughout the length thereof, the exerciser comprising right and left members, means seatable within the exerciser to maintain the two members axially interconnected for relative rotation in opposite directions, said means including a stem within the right member and extending a distance into the left member, a series of discs on said stem held against rotation

within said left member, a series of friction washers between said discs, said washers being held against rotation on said stem, means for retaining said discs and washers axially in closely spaced relation to each other, and externally operable means for moving said stem to bring said discs and washers into frictional engagement with each other thereby increasingly to resist relative rotation of the two members.

10. 7. A portable wrist exerciser of substantially uniform cylindrical shape throughout the length thereof, the exerciser comprising right and left members, means seatable within the exerciser to maintain the two members axially interconnected for relative rotation in opposite directions, said means including a stem within the right member and extending a distance into the left member, a spacer on the stem between the abutting inner ends of the tubular members, a series of discs on said stem held against rotation within said left member, a series of friction washers between said discs, said washers being held against rotation on said stem, means for maintaining said discs and washers axially in closely spaced relation to each other, and externally operable means for moving said stem to bring the discs and washers against said spacer and into frictional engagement with each other thereby increasingly to resist relative rotation of the two members.

30. 8. A portable wrist exerciser of substantially uniform cylindrical shape throughout the length thereof, the exerciser comprising right and left members, means seatable within the exerciser to maintain the two members axially interconnected for relative rotation in opposite directions, said means including a stem within the right member extending a distance into the left member, the latter having axially directed recesses in the inner end thereof, a series of discs on said stem held against rotation within the recesses of said left member, a series of friction washers between said discs, said washers being held against rotation on said stem, and externally operable means connected with the stem for moving said discs and washers into frictional engagement with each other thereby increasingly to resist relative rotation of the two members.

40. 9. A portable wrist exerciser of substantially uniform cylindrical shape throughout the length thereof, the exerciser comprising right and left members, means seatable within the exerciser to maintain the two members axially interconnected for relative rotation in opposite directions, said means including a stem within the right member extending a distance into the left member, the latter having axially directed recesses in the inner end thereof and slots circumferentially extending from said recesses near the inner end of the member, a series of discs having lips seatable in said recesses to maintain the disc unturned within the member, the innermost disc reaching a position of registration with said slots when the discs are seated in the member for rotating movement of its lips into said slots to check axial movement of the disc within the member, a series of friction washers between said discs, said washers being held against rotation on said stem, and externally operable means for moving said discs and washers against said innermost disc and in frictional engagement with each other thereby increasingly to resist relative rotation of the two members.

60. 10. A portable wrist exerciser of substantially uniform cylindrical shape throughout the length thereof, the exerciser comprising right and left

members, means seatable within the exerciser to maintain the two members axially interconnected for relative rotation in opposite directions, said means including a stem within the right member extending a distance into the left member, the latter having axially-directed recesses in the inner end thereof and slots circumferentially extending from said recesses near the inner end of the member, a series of discs having lips seatable in said recesses to maintain the disc unturned within the member, the innermost disc reaching a position of registration with said slots when the discs are seated in the member for rotating movement of its lips into said slots to check axial movement of the disc within the member, a series of friction washers between said discs, said washers being held against rotation on said stem, externally operable means for moving said discs and washers against said innermost disc and in frictional engagement with each other thereby increasingly to resist relative rotation of the two members, and means for locking the innermost disc against return rotation.

11. A portable wrist exerciser of substantially uniform cylindrical shape throughout the length thereof, the exerciser comprising right and left members, means seatable within the exerciser to

5 maintain the two members axially interconnected for relative rotation in opposite directions, said means including a stem within the right member extending a distance into the left member, said stem being internally threaded, a series of discs on said stem held against rotation within said left member, a series of friction washers between said discs, said washers being held against rotation on said stem, a screw in the end of the right member seated in the threads of the stem, and a cap on said screw, said cap being rotatable on the end of the member to move the stem axially to bring the discs and washers into frictional engagement with each other thereby increasingly to 10 15 resist relative rotation of the two members.
